FURNITURE

Harry E. Aulbrook, Detroit, Mich.

Application January 24, 1935, Serial No. 3,281

5 Claims. (Cl. 5—263)

My invention relates to furniture and particularly to a means for securing double conical springs to metal straps extending across the frame thereof.

Heretofore, double conical springs have seldom been employed with single straps which bridge opposite sides of a frame of furniture or the like. The single conical spring has usually been employed since it lends itself to ready application by its small end to such straps. When double conical springs have been employed heretofore they have usually been supported by a rigid member having upwardly extending end portions terminating in flanges overlying the upper edge of the frame structure elements which engaged opposite sides of the springs to support them in spaced relation to each other.

In practicing my present invention, I employ a relatively flexible metal strap suitably secured at opposite ends to opposite sides of the furniture frame element. Double conical springs are disposed in spaced relation to one another on the upper surface of the strip, preferably with strips of web material disposed crosswise of the straps interposed between the springs and the strap. Ties straddle the strap and engage the bottom turns of the springs and are secured to each other or to the straps for securely fastening the springs relative to each other and to the metal straps and web strips.

Accordingly, the main objects of my invention are: to provide a spring engaging tie which straddles the straps and engages the springs to retain the springs in fixed relation to each other and to the straps; to provide Y-shaped tie elements which span the strap and engage the lower turn of the spring and each other and/or the strap for fixing the spring relative to the strap; to provide Y-shaped ties which span the strap and engage the bottom turn of a double conical spring and each other to space the springs and secure them to the straps; to provide individual clips which span the strap and engage the lower turn of the springs and the strap in such manner as to fix the spring thereto; to provide a double Y-shaped tie which spans the strap and engages the lower turn of adjacent springs to retain the springs in firm fixed relation to the strap; and, in general, to provide securing means for double conical springs which are simple in construction, economical of manufacture and are readily applied to secure springs in fixed relation to a strap.

Other objects and features of novelty of my invention will be either specifically pointed out or will become apparent when referring, for a

better understanding of my invention, to the following description taken in conjunction with the accompanying drawing, wherein:

Figure 1 is a plan view, partly in section, of an upholstered frame embodying features of my invention.

Fig. 2 is an enlarged sectional view of the structure illustrated in Fig. 1, taken on the line 2—2 thereof.

Fig. 3 is one of the tie elements employed in the structure illustrated in Figs. 1 and 2.

Fig. 4 is cooperating tie elements likewise employed in the structure illustrated in Figs. 1 and 2.

Fig. 5 is a tie element similar to that illustrated in Fig. 4, showing a modified form thereof. 15

Fig. 6 is a view of structure, similar to that illustrated in Fig. 2, employing the tie element of Fig. 5, and

Fig. 7 is an enlarged view of structure similar to that illustrated in Fig. 1, showing a further 20 modified form of my invention.

Fig. 8 is a perspective view of one of the tie elements employed in the construction shown in Fig. 7.

As illustrated in Fig. 1, a plurality of spaced 25 parallel relatively thin and flexible metal straps 10 extend between the frame elements 11 and 12 of a piece of furniture, these straps being suitably secured at opposite ends to the frame members 11 and 12 in any suitable manner, that shown 30 forming no part of the present invention. The present invention includes means for securing and spacing the double conical springs 13 on the straps 10. Web strips 14 are preferably disposed normal to the straps 10, as illustrated in Fig. 1, 35 below the springs 13 to prevent the springs from producing undesirable sounds in use as might occur if directly contacting the metal straps 10.

In Figs. 3 and 4, I have illustrated one form of tie elements which I utilize in securing the 40 springs relative to the straps. In Fig. 3, I have illustrated a tie element 15 which engages the endmost spring at the end of the strap 10. The element is of Y shape and made preferably of spring wire, the central branch 16 of which is 45 reversely bent at 17 to provide an upstanding hook while the arms 18 and 19 are reversely bent at the ends to provide downwardly projecting hooks 21.

In Fig. 4 I have illustrated interrelated tie 50 elements 22 and 23, tie element 23 being of the same general type as the tie element 15 previously described with the exception that the reversely bent end portion 24 thereof is bent down in the same direction as the hooked end portions 55

21. Tie element 22 is likewise of the same general V shape as the other tie elements with downwardly extending end portions 21, but its central branch portion 25 is spaced apart to receive the 5 end 24 of a tie element 23 therein. The tie elements thus constructed are utilized for securing the springs 13 relative to the straps 10 by being located along the lower faces of the straps 10 and having their hooked end portions 21 extending upwardly beyond opposite side edges of the straps 10 and into hook-engaging relation with respect to opposite sides of the lower turn of cooperating springs 13 on the upper surface of the straps as indicated in Figs. 1 and 2.

15. In employing the tie elements 22 and 23 to secure springs to the upper face of a strap 10, a pair of springs 13 are placed upon the upper surface of the strap 10, preferably with a webbing strip 14 disposed between each spring 13 and the 20 strap 10, and with the springs 13 in more closely adjacent relationship than they will assume in the finished product. The hooked end 24 of a tie element 23 is then inserted into and between the opposite side of the central branch portion 25 of 25 a tie element 22. The hooked end portions 21 of the tie elements 22 and 23 are then swung upwardly relative to the point of connection of the tie elements and are caused to project upwardly in straddled relation beyond opposite edges of the 30 strap 10 between the aforementioned pair of springs 13 and into adjacent relationship with respect to adjacent sides of the lower turns of the springs. The hooked ends 21 are thereupon hooked over the corresponding lower turns of the 35 springs 13 and the springs 13 are thereupon moved apart so as to pull the stem portions of the elements 22 and 23 up into contact with the lower face of the strap 10.

This being accomplished, another spring 13 is 40 then placed in relatively close relationship to one of the above mentioned springs 13, on the upper face of the strap 10, and another pair of tie elements 22 and 23 are engaged in the above described manner with the lower turns of the last 45 positioned spring and the previously described spring next adjacent thereto, whereupon these last mentioned two springs are pulled apart to similarly bring the point of connection between these last mentioned tie elements 22 and 23 up 50 into contact with the lower face of the strap 10. This process is repeated until as many springs 13 are assembled upon the upper face of a strap 10 as may be required in the particular instance.

This being done, a tie element 15 positioned 55 below the strap 10 outwardly beyond an endmost spring 13 is moved to position the hooked ends 21 thereof upwardly beyond opposite side edges of the strap 10 and into engaging relationship with the adjacent side of the lowermost coil of said 60 end spring, and its hooked end 17 is thereupon moved upwardly into hooked relation with respect to the margins of an aperture 26 provided for its reception adjacent the corresponding end of the strap 10. This is easily accomplished because of the fact that the entire spring assembly 65 including the ties may be shifted on the strap 10 toward the aperture 26 to permit the introduction of the end 17 into the aperture 26.

Upon establishing one of the tie elements 15 in 70 the manner thus described, the entire spring assembly is thereupon shifted along the strap 10 toward the opposite end thereof. Another tie element 15 is then positioned to bring its hooked ends 21 into similarly engaging relation with respect to the endmost side of the lower turn of the 75

coil spring 13 at the opposite end of the strap, but in this case if the tie elements previously described have been formed to their proper lengths in relation to the apertures 26 formed in the opposite end portion of the strap 10, the hooked end 17 of the last mentioned tie member 15 will not be insertable into the corresponding aperture 26 without stretching the entire spring assembly including the springs 13 and the various tie elements 15, 22 and 23 lengthwise of the strap 10 beyond their normal positions. This stretching, however, is more or less readily effected upon suitable pressure being applied thereto lengthwise of the strap 10 due to more or less ready distortion of the lower coil of the springs 13 out of their normally true circular formation and at the same time effecting a greater or lesser reduction of the normal angle existing between the branches 18 and 19 of the various tie members and the central branch portions thereof. This stretching of the assembly will permit the hooked end 17 of the last mentioned tie member 15 to be inserted into its corresponding aperture 26 whereupon release of the stretching force mentioned the spring assembly will tend to return 25 to its normal position. This normal position, however, is preferably such that a small amount of tension still exists tending to pull the lower turns of the coils 13 out of their true circular shape and tending to reduce the normally free 30 angular relation between the branches 18 and 19 of the tie elements and their central branch portions. In this manner it is assured that no rattling will ever occur between the various tie members and springs 13 and strap 10.

It will be observed that because of the preferred relative width of the strap 10 with respect to the diameter of the lower turns of the springs 13 as indicated in the drawing, the hooked end portions 21 engage such lower turns at points materially spaced from the center of the strap and consequently lateral displacement of the springs 13 on the strap 10 is effectively prevented by the angularity existing between the points of the lower turns of the springs 13 engaged by the 45 hooked ends 21 as compared to the edge of the strap 10. Likewise, because of the fact that the main body portions of the various tie members are located below the strap 10, the springs 13 are effectively maintained downwardly into contact with the upper face of the strap 10 or the webs 14 interposed therebetween. Accordingly, by this simple means the springs 13 are securely and effectively secured and positioned in proper relationship with respect to each other and to the 50 strap 10.

In Figs. 5 and 6, I have shown a further form of tie element wherein two wires 28 and 29 are intertwined at 31 to form a unit element with upstanding arms 32 at each end, the ends of the 60 arms being spaced apart to straddle opposite edges of the strap 10 and reversely bent upwardly to provide hooks 33 at the top ends of the tie. These end hooks 33 of the ties readily span the edges of the strap 10 and, because they are 65 formed by bending the ends of the wires upwardly they may be caused to engage the lower turn of the springs 13 without any articulation of the tie element to thereby retain the springs 13 in predetermined spaced relation fixed to the strap. 70 End tie members 34 are employed and which are similar to the tie member 15 illustrated in Fig. 3 excepting that the ends are reversely bent upwardly at the top instead of downwardly to provide hooks 33' thereon which readily span oppo- 75

site edges of and engage the lower turns of the end springs in the manner illustrated in Fig. 6. The end 17 of these tie members 34 each engage an aperture in the strap 10 corresponding to the apertures 26 previously described for the purpose of retaining the springs relative thereto.

In Figs. 7 and 8 I have illustrated a different form of my invention wherein each of the springs 13 is individually secured in place on the strap 10 by a pair of tie members 35 of the type illustrated in Fig. 8. While the tie members for this modification may be of Y formation similar to that shown in Fig. 3, or a modification thereof, I prefer in the present case, because of the nature of the 15 connection, that the two branches of the tie cross each other to impart greater longitudinal flexibility to the same.

As illustrated in Fig. 8, each of these tie members is formed from a single piece of wire bent 20 upon itself at its midpoint to form a portion 36 and then downwardly in parallelism as at 37. The two branches of the wire are then bent outwardly away from each from the bottom of the 25 portions 37, as at 38, in an angular direction with respect to the longitudinal centerline of the tie member, and each branch is then reversely bent as at 39 to the opposite side of the tie member and the free end portions of each branch are then bent upwardly as at 40 and then horizontally as 30 at 41 away from the main body portion of the tie member and in substantial parallelism of the centerline thereof. From this it will be apparent that the portions 36 and 37 form a hook at one end of the tie member and facing away therefrom 35 while the portions 40 and 41 also form hooks which face in the opposite direction at the opposite end of the tie member.

In employing these tie members to secure a spring 13 to the strap 10, the strap 10 is centrally 40 provided with one or more openings to receive the hooked ends 36-37 of a cooperating pair of the members, a pair of such openings 42 being shown by way of illustration in adjacent but spaced relation with respect to each other longitudinally of the strap 10 on either side of the axial line of the spring 13 in its desired position. A pair of tie members 35 are then placed below the strap 10 with the hooked ends 36-37 thereof in opposed 45 relation, the portions 36 are inserted upwardly 50 each through its corresponding opening 42 with the body of the corresponding tie member extending radially outwardly of the spring 13 along the axis of the strap 10 and the end portions 41 are caused to pass upwardly beyond opposite sides 55 of the strap 10 and are hooked over the lower turn of the spring 13. In hooking the ends 41 over the lower turn of the spring 13, either or both the ties 35 and the lower turn of the spring 13 may be distorted, the cross portions 39 of the tie members 60 particularly adapting the tie members to be longitudinally contracted to permit this step of assembly. It may also be noted that the portions 41, when the tie members 35 are in their free state, are preferably positioned closer together 65 than the width of the strap 10 so that in assembling a tie member to the strap 10 the portions 41 must be sprung outwardly in order to project them upwardly beyond the side edges of the strap and when released resiliently clamp the opposite 70 edges of the strap 10 between them.

The tie members 35 are so proportioned with respect to the diameter of the lower turns of the springs 13 that when they are assembled in the position indicated in Fig. 7 they are maintained in 75 partially longitudinally contracted position, this

insuring against looseness and rattling of the parts and will insure that the parts will be resiliently maintained in the proper position at all times and without danger of becoming displaced.

With this construction, as in the previously described construction, the outer hooked ends of the tie members 35 cooperating with the lower turns of the corresponding spring 13 will maintain the spring 13 transversely of the strap 10 and in the construction illustrated in Fig. 7 a pair of 10 tie members 35 cooperate directly with the strap 10 to maintain the position of each spring 13 longitudinally of the strap.

While I have described and illustrated several embodiments of my invention, it will be apparent 15 to those skilled in the art that various changes, omissions, additions and substitutions may be made therein without departing from the spirit and scope of my invention as set forth in the accompanying claims.

20

I claim:

1. The combination with a metal strap extending between the sides of a frame of an element to be upholstered, double conical springs disposed thereon, tie elements positioned on the opposite side of the straps than that having the springs disposed thereon having branches which span the strap and engage the lower turn of each spring, and means integral with each of said tie elements engaging cooperating means of another tie element.

2. The combination with a metal strap extending between the sides of a frame of an element to be upholstered and having apertures therein adjacent its end, double conical springs 35 disposed thereon, tie elements positioned on the opposite side of the strap than that having the springs disposed thereon having branches which span the strap and engage the lower turn of the spring, means on said tie elements engaged 40 with each other and second tie elements spanning the strap and engaging the lower turn of the end springs and having additional hooks which terminally engage the walls of said apertures in the strap with opposite sides of the 45 hooks overlying opposite sides of the strap for retaining the springs against longitudinal movement relative to the strap.

3. The combination with a strap for interconnecting the frame of an element to be upholstered, of web elements terminally secured relative to the frame and intersecting the strap substantially at right angles above and in contact therewith, a spring disposed at each point of intersection between the strap and web elements, 55 tie elements spanning said strap and interconnecting the lower turns of the springs to each other and to the strap, and additional tie elements spanning said strap and engaging the lower turn of the endmost springs for fixing all 60 of said springs against movement longitudinally of the strap.

4. The combination with a plurality of straps disposed across a frame of an element to be upholstered, of web elements disposed across 65 said frame above and in angular relation to said straps, a spring disposed at each point of intersection of the strap and web elements and resting on said web element on one side of said straps, tie elements disposed on the opposite 70 side of said straps spanning said straps and engaging the lower turns of said springs, means interconnecting the tie elements to each other, tie elements engaging the endmost springs, and means securing said end tie elements in fixed 75

relation to retain said springs against longitudinal movement relative to said strap.

5. The combination with a plurality of metal straps extending between the frame members of an element to be upholstered, of web elements extending likewise and intersecting said straps at an angle above and in contact therewith, a double conical spring disposed on one side of said straps and said webs at each point of intersection, tie elements means disposing on the op-

posite side of said straps spanning said straps and interconnectingly engaging the lower turns of adjacent springs for holding the springs in a spaced relation, end tie elements engaging the lower turn of endmost springs, and means fixing the end tie elements relative to said strap for retaining the springs against longitudinal movement relative thereto.

HARRY E. AULSBROOK. 10
